UNITED STATES PATENT OFFICE.

CLARENCE S. ZINK, OF MARSHALL, MISSOURI.

DEVICE FOR TESTING WORKING OF MAGNETOS, &c.

1,199,145.

Specification of Letters Patent. Patented Sept. 26, 1916.

Application filed March 10, 1915. Serial No. 13,414.

To all whom it may concern:

Be it known that I, CLARENCE S. ZINK, a citizen of the United States, residing at Marshall, in the county of Saline and State 5 of Missouri, have invented certain new and useful Improvements in Devices for Testing Working of Magnetos, &c.; and I do hereby declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in indicators adapted to show the working of a magneto and coil at a glance to determine as to whether or not the 20 sparking is working properly.

The invention consists of various details of construction, combinations and arrangements of parts which will be hereinafter 25 fully described, shown in the accompanying drawings and then specifically defined in the appended claim.

My invention is illustrated in the accompanying drawings, in which:—

Figure 1 is a central vertical sectional 30 view through the apparatus. Fig. 2 is a front elevation, and Fig. 3 is a rear view.

Reference now being had to the details of the drawings by letter, A designates a casing, one end of which is provided with a 35 plurality of recesses, four being designated by letter B, although it will be understood that the invention is not confined to any particular number, four being illustrated to show the application of the invention in connection with a four cylinder engine, and the 40 face C of the casing about the marginal edge of the openings is preferably white in order to be easily discerned, and in the bottom of each recess is a reflector D. Terminals, 45 designated by letter T, are mounted in and project from the opposite ends of the casing and each extending into a recess B, and F designates screws, suitably insulated and mounted in apertures in the walls of the 50 chamber and of any suitable conducting material and are adapted to be adjustable relative to the terminals E² where the sparking may take place and be reflected by the

reflector and made visible. A bull's eye H is held over the recesses by means of a ring 55 I which is held in the casing in any suitable manner.

Conducting members, designated by letter K, communicate at their inner ends with the terminals E, being held in contact therewith by the nuts L, while adjustable terminal binding nuts, designated by letter O, are properly insulated and are connected to the conductors Q which in turn have connection with the terminals R and to which terminals 60 connections are made with the magneto coils and with the terminals of the sparking plugs, the said conductors Q in turn being connected to the screws D.

In operation, the apparatus being connected up to the sparking plugs and coils and magneto in the manner shown and described, in the event of the magneto operating correctly, the spark will appear between each of the terminals in front of the 70 reflectors in the recesses but, in the event of any particular coil not operating, the lack of a spark at the terminals in front of any particular reflector will designate that such coil is not in working order, hence the corresponding 75 sparking plug will not be in operation.

By reason of the particular construction of the apparatus, it will be noted that a visible means is afforded whereby it may be 80 readily determined which, if any, of the 85 sparking plugs is not in operative condition, either by day or night, the face of the casing being painted, preferably of a light color, so that the recesses will be plainly 90 discernible.

What I claim to be new is:—

A device for testing the working of a magneto and coil comprising a casing having one end contracted and its other end 95 enlarged and recessed with intersecting partitions forming compartments, said casing being provided with longitudinal apertures leading into the compartments, terminals extending through said longitudinal apertures and terminating at corresponding 100 ends, one in each of said compartments and bent in planes at right angles to the lengths of the casing, their opposite ends bent at angles and bearing against the end of the 105 casing and extending beyond the circum-

ference of the contracted portion of the casing, conductors passing through apertures in the casing and having eyes at corresponding ends, screws passing through the walls of the recesses and engaging said eyes and having adjustments therein, reflectors mounted one in each compartment intermediate the adjacent ends of said terminals

and screws and the bottoms of the compartments.

In testimony whereof I hereunto affix my signature in presence of two witnesses.

CLARENCE S. ZINK.
